W. HAUFF,
C. WAHLERS.

United States Patent Office.

EDWIN JOHN GODFREY, OF NEW YORK, N. Y.

Design No. 3,658, dated September 14, 1869.

DESIGN FOR MOURNING-CARDS.

The Schedule referred to in these Letters Patent and making part of the same.

To all whom it may concern:

Be it known that I, EDWIN JOHN GODFREY, of the city, county, and State of New York, have invented a new and original Design for Mourning-Card; and I do hereby declare the following to be a full, clear, and exact description thereof, which will enable those skilled in the art to make and use the same, reference being had to the accompanying drawing, forming part of this specification, which drawing represents a face view of this design.

My design consists in a semi-cylindrical escutcheon, separated from the bottom of the card, on its convex side, by a border composed of a succession of scallops, while the outside border of the card itself consists of a wide black line, with a narrow light edge on its outside in such a manner that a mourning-card of a novel and elegant appearance is produced.

In the drawing,

The letter A designates a semi-cylindrical escutcheon, which is separated from the body of the card by a border, *a*, composed of a series of scallops, as shown.

The outside border of the card is composed of a wide black line, *b*, and a narrow light line, *c*, which forms the outer edge of the card.

What I claim as new, and desire to secure by Letters Patent, is—

The design for a mourning-card, as herein shown and described.

EDWIN J. GODFREY.
